(57) **CLAIM**

The ornamental design for a low-profile cap for modular panel systems, as shown and described.

DESCRIPTION

FIG. 1 is an exploded perspective view of a low-profile cap for modular panel systems in an exemplary environment;

FIG. 2 is an assembled right elevation view thereof in an exemplary environment;

FIG. 3 is a top perspective assembled view thereof;

FIG. 4 is an exploded perspective view thereof in an exemplary environment;

FIG. 5 is a top perspective assembled view thereof in an exemplary environment;

FIG. 6 is a frontal elevation view thereof;

FIG. 7 is a rear elevation view thereof; and,

FIG. 8 is a right elevation view thereof.

The broken lines showing bolts and attachment sleeves are for illustrative purposes only and form no part of the claimed design.
